US00D720727S

(12) **United States Design Patent**
Yu

(10) **Patent No.:** **US D720,727 S**
(45) **Date of Patent:** **** Jan. 6, 2015**

(54) **SIREN SWITCH**

(71) Applicant: **Ningbo Yinzhou Self Photoelectron Technology Co., Ltd.**, Ningbo, Zhejiang (CN)

(72) Inventor: **Feng Yu**, Zhejiang (CN)

(73) Assignee: **Ningbo Yinzhou Self Photoelectron Technology Co., Ltd.**, Ningbo (CN)

(**) Term: **14 Years**

(21) Appl. No.: **29/458,929**

(22) Filed: **Jun. 24, 2013**

(30) **Foreign Application Priority Data**

Feb. 1, 2013 (CN) 2013 3 0032886

(51) **LOC (10) Cl.** **14-01**

(57) **CLAIM**

The ornamental design for a siren switch, as shown and described.

DESCRIPTION

FIG. 1 is a perspective view of a siren switch of my new design;

FIG. 2 is a front view of the siren switch thereof;

FIG. 3 is a rear view of the siren switch thereof;

FIG. 4 is a left view of the siren switch thereof;

FIG. 5 is a right side view of the siren switch thereof;

FIG. 6 is a top side view of the siren switch thereof; and,

FIG. 7 is a bottom view of the siren switch thereof.

The dash lines represent the elements that do not form part of the claimed design.

1 Claim, 6 Drawing Sheets
